UNITED STATES PATENT OFFICE.

RALPH V. SAGE, OF COLUMBUS, OHIO.

CAR-UNDERFRAME.

1,128,054.

Specification of Letters Patent.

Patented Feb. 9, 1915.

Application filed May 1, 1914. Serial No. 835,592.

To all whom it may concern:

Be it known that I, RALPH V. SAGE, a citizen of the United States, residing in the city of Columbus, in the county of Franklin and State of Ohio, have invented certain new and useful Improvements in Car-Underframes; and I do hereby declare the following to be a full, clear, and exact description of the invention, such as will enable others skilled in the art to which it appertains to make and use the same.

My invention relates to railway cars and more particularly to freight box car underframes which are constructed entirely of metal, this construction having been shown and not claimed in my Patent No. 1,059,770, dated April 22nd, 1913, filed August 3rd, 1911.

The principal objects of my invention are to produce a metal box car underframe which can easily be constructed, is light in weight, and of sufficient strength and rigidity to withstand the rough usage to which a car of this kind is subjected.

The construction of the bolsters forms another object of my invention. These bolsters are made of four pressed metal plates formed into shallow box shaped members with outwardly extending flanges. Two of these shallow box shaped members are disposed on either side of the center sill, with their webs back to back and in contact with each other and having their inner flanges riveted together through the single center sill. The bottom flanges of the bolsters are tied together by means of a bottom cover plate, while the tops are tied together by a top cover plate.

Still another novel feature is the central floor cover plate which covers the central meeting edges of the floor plates and also reinforces the center sill.

An embodiment of my invention is shown in the accompanying one sheet of drawings, 45 in which like characters indicate like parts.

Figure 1 is a horizontal section taken on the line I—I of Fig. 2; showing parts of the floor plates broken away to expose the underframes, Fig. 2, is a vertical transverse section taken on the line II—II of Fig. 1, and Fig. 3 is a detail sectional view.

Referring now to the various characters of reference upon the drawings, my car underframe structure comprises a center sill 1 of any approved form but preferably as shown here of a single I-beam to the end of

which, between the bolsters 2 and the end sills 3, are attached the channel draft sills 4, these being spaced apart to receive the draft gear, and their inner ends bent inwardly as shown in Fig. 1 so as to embrace the vertical web of the I-beam center sill 1, while their outer ends are attached to the end sills 3.

The bolsters 2 are built up of four pressed metal plates of similar size and shape, but rights and lefts formed into shallow box shaped members with flanges 5 extending outwardly and entirely around the edges of the same. These pressed metal members are disposed in pairs on either side of the center sill, and placed back to back with their webs in contact, the flanges extending outwardly. On the inner side the flanges 5 are connected together through the center sill 75 by means of rivets as shown at 6 while the floor plates 9 and 10 and the cover plates 7 are attached to the upper flange. The central and end portions of the bottom flanges extend horizontally parallel to the top portion with an inclined portion between the deeper center and the shallower end. The inner parts of these box shaped members are of the same depths as the center sill 1 so that the bottom horizontal bottom plate 8 ties 80 them together, but the outer end is of less depth corresponding to the depth of the side sill to which it is attached, thereby forming an efficient construction for the purpose intended.

The floor of the car is made of plates 10 between the bolsters which have their meeting edges on top of the center sill covered by a cover plate 11 which also reinforces and protects the center sill. The ends of the 95 floor between the bolsters and end sills are composed of the plates 9 secured to side sills, end sills and draft sills as shown. The plates 10 are also riveted to and supported by the transoms 12 which are spaced at suitable distances apart between the bolsters and have their ends attached to the center and side sills of the car.

13 designates the side plates of the car which have integral outwardly extending 105 flanges 14 along their vertical edges by means of which the side plates are riveted together and act as the side stakes of the car. If desired, a strip 15 or other strengthening members may be inserted between 110 these flanges to further stiffen the sides of the car. The lower ends of the side plates

13 are riveted directly to the side sills 16 which are of channel shape and extend the full length of the car with their flanges turned inwardly toward the center of the 5 car.

Although I have shown and described my improvements in considerable detail, I do not wish to be limited to the exact and specific details shown and described, but may 10 use such substitutions, modifications or equivalents thereof, as are embraced within the scope of my invention or as pointed out in the claims.

Having thus described my invention, what 15 I claim and desire to secure by Letters Patent is:—

1. A car provided with a single center-sill of rolled section which terminates between the bolsters and the end sills, floor 20 plates having their meeting edges on the said single center sill, draft-sills spliced to the body of the center-sill between the bolsters and the end-sills, and a cover plate laid over the meeting edges of the floor 25 plates and attached to the center-sill.

2. A car provided with a center-sill which consists of a continuous member that terminates between the bolsters and the end-sills, draft-sills spliced to the body of the center-sill between the bolsters and the end sills, and pairs of pressed metal bolster members 30 disposed on either side of the center-sill and attached together through the center sill.

3. A car provided with a center-sill which 35 consists of a continuous member that terminates between the bolsters and the end-sills, draft-sills spliced to the body of the center-sill between the bolsters and the end-sills, and pairs of flanged bolster members 40 disposed on either side of the center-sill and having their inner flanges attached together through the center-sill.

4. A car provided with a center-sill which

consists of a continuous member that terminates between the bolsters and the end-sills, draft-sills embracing and attached to the ends of the center-sill, and flanged bolster members disposed in pairs on either side of the center-sill with their webs in contact, the inner outwardly extending flanges being 50 attached together by a single set of rivets through the center-sill.

5. In a railway car, provided with a center sill, side-sills and end-sills, a bolster built up of shallow open box shaped members having a vertical web and integral transversely extending flanges, disposed in pairs on either side of the center sill, the webs of said shallow box shaped members being placed back to back and in contact, while the adjacent inner outwardly extending flanges are riveted together through the center-sill.

6. In a railway car provided with a center-sill, side-sills and end-sills, a bolster built up of shallow open box shaped members each having a vertical web and integral transversely extending flanges, disposed in pairs on either side of the center-sill, the webs of said shallow box shaped members 70 being placed back to back and in contact with each other, the inner adjacent outwardly extending flanges being riveted together through the center-sill, the central portion of said open shallow box shaped 75 members being of substantially the same depth as the center-sill, while the outer ends are of less depth, and corresponding to the depth of the side sills to which they are attached.

In testimony whereof I hereto affix my signature in the presence of two witnesses.

RALPH V. SAGE.
